CLAIM

The ornamental design for a model vehicle hood vent as shown and described.

DESCRIPTION

FIG. 1 is an upper, left, front perspective view of a model vehicle hood vent showing our new design;

FIG. 2 is an upper, right, rear perspective view thereof;

FIG. 3 is a lower, right, front perspective view thereof;

FIG. 4 is a lower, left, rear perspective view thereof;

FIG. 5 is an upper plan view thereof;

FIG. 6 is a lower plan view thereof;

FIG. 7 is a right side elevation view thereof;

FIG. 8 is a left side elevation view thereof;

FIG. 9 is a front elevation view thereof; and,

FIG. 10 is a rear elevation view of the model vehicle hood vent.

In the drawings, the broken lines illustrate portions of the model vehicle hood vent that form no part of the claimed design.

In the drawings, only the first embodiment of the model vehicle hood vent is shown. The second embodiment of the claimed design is a right side model vehicle hood vent which is a mirror image of the left side model vehicle hood vent disclosed in the first embodiment.
